UNITED STATES PATENT OFFICE

IRA H. DERBY, OF INDIANAPOLIS, INDIANA, ASSIGNOR TO PETER C. REILLY, OF INDIANAPOLIS, INDIANA

RETORT

Application filed March 6, 1929. Serial No. 344,797.

This invention relates to a device, which, because it involves some of the characteristics of a still, and some of the characteristics of a retort, and because it is rotated to carry out the process of my copending application Serial No. 344,796 filed March 6, 1929 I shall designate as a rotary still retort.

The application above mentioned relates to a process of distilling fluent materials, the process, generally stated, comprising the distillation of liquids or granular solids, or a mixture of the two, in a retort, preferably cylindrical, the retort being rotated preferably on its longitudinal axis during the distilling operation, and the speed of rotation being such that the material is distributed in a relatively thin layer on the cylindrical walls of the retort. The purposes accomplished are:—

The thickness of material is reduced and the effective heating area of the still is increased by the distribution of the charge in a relatively thin layer over substantially the entire internal surface of the still; the heat transfer is accelerated, first, by the rapid motion of the exterior of the still in contact with the hot gases, and, second, by the flow of the charge, in case of liquids, over the internal surface of the still. In the case of liquid charges, the tendency to foam, which heretofore has imposed very serious limitations on the rate of heating, is almost entirely suppressed by centrifugal force, thus eliminating a serious source of trouble encountered in past practice. In the case of fluent granular solids, the dust generated during the distilling operation is retained adjacent to the wall of the still by centrifugal action instead of passing off in suspension with the volatile products, as heretofore.

The present application is directed to the structural details of the mechanism by which the process above identified may be carried out commercially.

Generally stated, the apparatus includes a cylindrical shell, which forms the still or retort, which is mounted on rotating heads by means of a shrink fit. As an incident to this construction, means are provided to chill the heads to shrink them away from the shell

prior to withdrawal. There is also a device which supports the shell during and after the withdrawal of the heads, and which may be operated to shift the shell to a position in which the coke residue may be removed.

The device is applicable to processes in which the material is treated at pressures other than atmospheric, or in which steam or other gases or vapors are passed through the still.

Other features of the invention are,— special means for charging the still or retort either with solids or with liquids, and means for condensing and recovering waxes and oils which pass off from the still in a vapor state.

In the drawings certain incidental or accessory apparatus has been omitted or only partially shown in order to simplify the illustration. The drawings are thus confined to the fundamental or essential elements making up the still-retort.

In the drawings,—

Fig. 1 is an elevation, largely in vertical axial section, showing the complete device.

Fig. 2 is a section on the line 2—2 of Fig. 1.

Fig. 3 is a plan view, partly in section on the axis of the rotary still.

Fig. 4 is a section on the line 4—4 of Fig. 3.

Fig. 5 is a view, similar to Fig. 3, but showing the heads withdrawn from the shell and the shell rotated to position for the discharge of the coke residue.

Fig. 6 is a detail in longitudinal section of a charging tube with conveyor, which may be used to charge the device with granular material.

Fig. 7 is a detail view showing a portion of the mechanism for controlling the axial position of the shafts, and thus controlling the advance and retraction of the heads of the still.

11 represents the furnace chamber which is enclosed by a metal shell 12 having a lining 13 of refractory material. This shell may be heated internally in any suitable manner, but I prefer and illustrate gas burners 14 by which the gas generated in the distilling operation may be burned with such additional gaseous or other fuel as may prove necessary. The products of combustion are discharged

at 15 and pass off through any suitable off-take, heat economizer, etc., not shown.

The furnace chamber 11 is formed with two extensions 16 and 17 extending in alignment with each other in opposite directions, and at an angle to the axis of the chamber 11. During the charging and discharging operations the rotary retort, hereinafter described, is brought into alignment with these extensions 10 to permit the passage of a rammer for the purpose of ejecting the charge, and in some cases to receive a charge, notably when the charge is inserted as a cartridge. Obviously the material, either granular or liquid, might be inserted in the form of a cartridge which is disrupted by heat.

The extension 16 is provided with a hinged door 18, while the extension 17 is closed by a head 19. A rammer head 21 is mounted on 20 a plunger 22 which may be shifted in the direction of its axis so as to traverse the head 21 in alignment with the common axis of the extensions 16 and 17. The shaft 22 is long enough to traverse the head 21 the entire 25 length of the retort when this is moved to the position of Fig. 5. A gland 23 may be provided to prevent leakage of gas from the furnace chamber 11.

Alined with each other and coaxial with 30 the cylindrical furnace chamber 11 are two shafts 24 and 25. Both these shafts are hollow, as illustrated. The shaft 24 is supported in a long bearing 26 and the shaft 25 is supported in two such bearings 27 and 28, spaced apart to confine between them a sleeve 29 which carries a sprocket wheel 31. The sprocket wheel 31 is splined at 32 to the shaft 25. It follows that the sprocket 31 may drive the shaft 25 without restricting the freedom of the shaft 25 to move longitudinally in its bearings. Power is transmitted from a motor 33 through a sprocket 34 and chain 35. Any equivalent driving means might be substituted.

45 The shaft 25 has a reduced extension 36 which extends beyond the bearing 28 and turns in stuffing boxes 37 and 38 at the points where it passes through the walls of the chamber 39. The end of the shaft is plugged 50 at 41. Similarly the shaft 24 has a reduced extension 42 beyond the bearing 26 and this passes through a chamber 43 similar to the chamber 39 and makes tight joints therewith by means of the stuffing boxes 44. The end 55 of the shaft is plugged at 45, the plug being removable, as in the case of the plug 41. Either or both of the chambers 39, 43, may be provided with means for charging liquid through the hollow shaft or for withdrawing 60 volatile products flowing out through the shaft, or both, but to simplify the drawings I have shown such mechanism applied only to the extension 42.

Within the chambers 39 and 43 the extensions 36 and 42 are formed with lateral ports

46, 47. Overlying the port 47 is a connection 48 leading from a liquid reservoir 49, which connection is controlled by valve 51. Leading from the top of the chamber 43 is a connection 52 which leads to a condensing coil 53 enclosed in a chamber 54 through which the cooling liquid may be circulated. Any material, such as oils or waxes, condensed in the coil 53 may be collected in a receptacle 55, or any equivalent means may be used for 75 collecting them.

The retort is made up of an open ended cylindrical shell 56 having annular reinforcing thickened portions 57 at its two ends. Within these thickened portions the shell 56 receives two hollow heads 58, which are identical with each other, and one of which is fixedly mounted on the inner end of the shaft 24 and the other of which is fixedly mounted on the inner end of the shaft 25.

80 The reason for making the heads 58 hollow is to permit the circulation through them of a cooling fluid, such as steam or steam charged with water, at those times when it is desired to shrink the heads away from the shell. Connections for effecting the circulation are established temporarily by means hereinafter described.

85 After the heads have been shrunk they are retracted from the shell 56 by moving the shafts 24 and 25 longitudinally outward from the chamber 11. The mechanism for accomplishing this function is identical in the case of the shaft 24 and the shaft 25 and the same reference numerals will be applied 100 to similar mechanisms.

The retracting device includes a yoke 61 which has a swivel connection 62 (see Fig. 7) with a shaft 24 or 25 as the case may be, the swivel connection being adjacent the junction between the shafts 24 and 25, and their reduced extensions 42 and 36.

105 Threaded in the two opposite ends of each yoke 61 are two lead screws which are swiveled at their opposite ends 64 in a frame 110 structure 65 which sustains the entire mechanism. The lead screws 63 are connected to rotate in unison by a sprocket chain 66 which runs on two sprockets 67 of equal size, one mounted on each lead screw. A hand wheel 68 is provided to turn one and therefore both the lead screws.

115 The hollow heads 58 are ported, as indicated at 71, to receive two nozzles 72 which are mounted in guides 73, so as to be capable of longitudinal motion into and out of sealing engagement with the ports 71. These are the nozzles through which the cooling medium above mentioned is circulated and this liquid is fed in and withdrawn through 120 respective flexible tubes 74 and 75. This mechanism is identical for each of the heads 58, and the parts are similarly numbered in the two instances.

125 During and after the retraction of the 130

heads, the shell 56 which is normally sustained by the heads, must be otherwise supported. For this purpose I make use of a fluid pressure lift including a cylinder 76 with a vertical piston rod 77 and an arcuate cradle 78 which may be raised by the rod into supporting engagement with the shell 56.

In some cases it may prove inexpedient to 10 insert the charge in the form of a cartridge, or to feed liquid material in through one of the rotary shafts, which is usually the preferred operation, and to meet such a contingency I may make use of a charging tube, 15 illustrated in Fig. 6. This is inserted longitudinally through either of the shafts 24, 25, after removing the end plug 45 or 41, as the case may be. Such a tube is indicated at 81. It is of such a diameter that 20 it may pass through the hollow bore of the shaft, and when fully inserted will extend substantially to the far end of the retort. It is provided with a feeding hopper 82 and a longitudinal screw conveyor element 83, 25 which may be rotated by any suitable means typified by the hand crank 84. In charging with this device the charging tube is inserted so that it discharges the material at the far end of the retort, and is then gradually withdrawn 30 while discharging the material, so as to distribute this throughout the entire length of the retort. The retort should be rotated during this operation. At the completion of charging the tube is withdrawn and the end plug reinserted in the shaft.

The operation may be summarized as follows:

The retort may be charged in any one of the several different ways suggested, depending 40 on the particular material being charged. That is to say, the liquid may be fed in through one of the hollow shafts from a reservoir such as 49; it may be fed in with the charging tube, as just described, or it may be inserted in the form of a cartridge while the mechanism stands in the position of Fig. 5.

In the first two methods of charging the parts will stand in the position of Fig. 3. In the third method of charging the rammer head 21 will be retracted, the piston rod 77 will be rotated by any suitable means to bring the shell 56 into alignment with the heads 58. It will be understood that at this time the heads are cooled, and in their cooled 55 condition will be advanced by rotating the wheels 68 so that each end enters a corresponding end of the shell 56. Thereupon circulation of cooling fluid is terminated to cause the expansion of the heads and their frictional retention in the ends of the shell.

The minimum speed of rotation of the shell is that at which the material is distributed by centrifugal force in a substantially uniform layer over the entire surface of the shell 56.

60 The rate of heat transfer can be greatly in-

creased by the use of higher speeds, and other advantages can be secured with some materials as has been demonstrated in practice.

Heat is applied at a proper rate and the volatile products pass off through one or both of the hollow shafts, according to whether one or both of the receptacles 49 and 55 be equipped with off-takes. Condensable vapors are condensed in the coils 53, as described. Non-condensable gases are put to any appropriate use. For example, they may be collected and used in heating the chamber 11, but the means for accomplishing this result is not illustrated, as it is a familiar expedient in this art.

70 During the distilling operation with liquids, particularly toward the end, there is a tendency for violent foaming to occur, because of the rapid evolution of gases and vapors. This tendency is almost entirely suppressed by centrifugal force, thus allowing 75 the more rapid application of heat.

80 From this it results that the process is more expeditiously carried out, and the final coke product is more uniform and of a finer grain 85 and more solid texture, than has heretofore been secured.

85 The application of heat is continued until substantially all the volatile materials have passed off and the coke residue shrinks away 90 from the shell 56. At this time the rotation is stopped, the shafts are turned to the proper position to permit entry of the connectors 72 into the ports 71, the connectors are advanced into contact, and the cooling liquid 95 is turned on. This shrinks the heads away from the shell. At or about the same time, the hoist is elevated until the cradle 78 engages the shell 56. As soon as the heads have 100 shrunk they are retracted by rotating the hand wheel 68. After this, piston rod 77 is rotated until the shell 56 stands in alignment with the extensions 16 and 17. The door 18 is then opened and the rammer 21 is pushed through the shell 56 to discharge the coke 105 residue. This having been done, the device 110 is recharged and the operation repeated.

115 As stated, only the essential elements of the device have been illustrated in detail, the minor or accessory parts not being a part of the invention and their design involving only ordinary mechanical skill. Furthermore, the exact mechanisms illustrated need not be adhered to but are susceptible of variation without departing from the invention. In fact 120 with certain special materials and under certain circumstances, other special arrangements may be availed of. The shafts, heads, shell, and all other parts subject to severe heat, may be, and preferably are, constructed 125 of special alloys chosen for the purpose.

130 What is claimed is,—

1. The combination of a furnace chamber; a cylindrical shell therein having open ends; a pair of head members for closing said ends

movable into and out of sealing engagement with said shell; and means attached to said ends for supporting and for rotating said heads and the shell supported thereby.

5 2. The combination of a furnace chamber; a substantially horizontal open-ended cylindrical shell therein; a pair of head members movable into and out of sealing engagement with the open ends of said shell; and means connected to said heads for rotating the same and the shell supported thereby on a substantially horizontal axis.

10 3. The combination of a furnace chamber; an open-ended cylindrical shell therein; a pair of head members movable into and out of sealing engagement with said shell; means connected to said heads for rotating the same and the shell supported thereby when the heads are in engagement therewith; secondary means for supporting said shell when said head members are retracted; and means for ejecting solids from said shell while supported by said secondary means.

15 4. The combination with a furnace chamber of a pair of heads rotatably mounted therein; a cylindrical shell adapted to make a shrink fit with said heads when the heads and shell are at equal temperatures, said heads, during the interval of the heating operation, supporting said shell; means for establishing a temperature differential between said heads and shell; and means for withdrawing said heads from said shell.

20 5. In combination with a furnace chamber of a pair of heads rotatably mounted therein; a cylindrical shell encircling said heads adjacent its ends so as to be supported thereby and making a shrink fit with said heads when the heads and shell are at equal temperatures; means for cooling said heads while the shell remains heated; and means for withdrawing said heads from the shell while so cooled.

25 6. In a retort, the combination of an open-ended shell; at least one removable head therefor with which the shell makes a shrink fit when the two are at equal temperatures; and means for establishing a temperature differential between the head and shell, to permit withdrawal of the head.

30 7. In a retort, the combination of an open-ended shell; at least one removable head therefor adapted to fit into the open end of said shell and to make a shrink fit therewith when the head and shell are at substantially equal temperatures; and means for cooling said head while the shell remains heated, to permit withdrawal of the head.

35 8. A device for treating fluent material, comprising in combination a furnace chamber; a retort in said chamber; shafts upon which said retort is rotatably supported, at least one of said shafts having a fluid conducting passage; means for rotating said retort at a speed at least sufficient to distribute the fluent material by centrifugal force in

a substantially uniform layer over the walls of the retort; and means to feed fluent material to the retort through a passage in one of the shafts.

40 9. A device for treating fluent material, comprising in combination a furnace chamber; a retort in said chamber; shafts upon which said retort is rotatably supported, at least one of said shafts having a fluid conducting passage; means for rotating said retort at a speed at least sufficient to distribute the fluent material by centrifugal force in a substantially uniform layer over the walls of the retort; and means to condense vapors flowing from the retort through a passage in one of the shafts.

45 10. A device for treating fluent material, comprising in combination a furnace chamber; a retort in said chamber; shafts upon which said retort is rotatably supported, at least one of said shafts having a fluid conducting passage; means for rotating said retort at a speed at least sufficient to distribute the fluent material by centrifugal force in a substantially uniform layer over the walls of the retort; means to feed fluent material to the retort through a passage in a shaft; and means to condense vapors flowing from the retort through a passage in one of the shafts.

50 11. The combination of a furnace chamber; a pair of heads mounted in said chamber to rotate on aligned axes respectively and to be movable relatively toward and from each other; an open-ended shell with which said heads may enter into and withdraw from supporting and sealing engagement through said relative movement of the heads; a supporting device movable into supporting relation with the shell and rotatable to shift the shell into and out of alignment with said heads when the latter are withdrawn; and means associated with said furnace chamber for discharging solid residues from said shell when the latter is shifted from alignment with said heads.

55 12. The combination of a furnace chamber; a pair of heads mounted in said chamber to rotate on aligned horizontal axes respectively and to be movable relatively toward and from each other; an open-ended substantially cylindrical shell with which said heads enter into and withdraw from supporting and sealing engagement by the relative movement of the heads; a supporting member movable into and out of supporting relation with the shell and upon which the shell is rotatable to shift the shell into and out of alignment with said heads; and means associated with said furnace chamber for discharging solid residues from the shell when the latter is shifted from alignment with said heads.

60 13. The combination of a furnace chamber; a pair of hollow heads mounted in said chamber

ber to rotate on aligned horizontal axes respectively and to be shiftable axially toward and from each other; an open-ended substantially cylindrical shell which encircles said heads and forms a shrink fit therewith when the heads and shell are at substantially equal temperatures, said heads during the interval of the heating operation forming a support for the cylindrical shell; means for circulating cooling fluid through said heads to shrink the same free from said shell; a supporting device movable into and out of supporting relation with the shell and rotatable to shift the shell into and out of alignment with the heads when the latter are retracted; and means for discharging solid residues from the shell when the latter is moved out of alignment with said heads.

14. In combination with a furnace chamber, a cylindrical shell located therein; a pair of heads also located within said chamber and fitting the ends of the shell; means for rotating at least one of said heads; and means located beneath the shell and within the chamber for contacting the shell and supporting the same.

15. In combination with a furnace chamber having laterally disposed aligned extensions, a cylindrical shell mounted within the chamber; a pair of heads likewise within the chamber and fitting the ends of the shell; means for rotating at least one of said heads and thereby imparting rotary motion to the shell; and means located within the lower portion of said chamber for supporting the shell when the same is at rest, said means being movable toward and from the shell and rotatable about a vertical axis whereby the shell may be swung laterally when the heads are withdrawn from engagement therewith.

In testimony whereof I have signed my name to this specification.
